United States Patent [19]

Evans, Jr. et al.

[11] Des. 245,897

[45]  Sept. 27, 1977

[54] APPLIQUE FOR A CANDY BOX

[76] Inventors: John Clinton Evans, Jr., P.O. Box 138, North Olmsted, Ohio 44070; Harold Eugene Kautz, 5923 Clearview Drive, Parma Heights, Ohio 44130

[] Term: 14 Years

[21] Appl. No.: 597,147

[22] Filed: July 18, 1975

[51] Int. Cl. .... D9—99

[52] U.S. Cl. D9/245

[58] Field of Search ..... D9/171, 195, 199, 217, D9/225, 227, 244, 245, 269, 272; 229/16 R, 8, 220/62, 376; 206/457, 491

[56]

References Cited

U.S. PATENT DOCUMENTS

D. 52,767	12/1918	Joslin	D9/227
D. 61,310	8/1922	Kelsey et al.	D9/227
D. 82,614	11/1930	Lippmann	D9/225
D. 114,476	4/1939	Smoleroft	D9/191
D. 167,152	7/1952	Kornblau	D9/224

Primary Examiner—Joel Stearman

Assistant Examiner—Louis S. Zarfas

Attorney, Agent, or Firm—John C. Evans, Jr.

[57]

CLAIM

The ornamental design for an applique for a candy box, substantially as shown and described.

DESCRIPTION

The FIGURE is a top plan view of an applique for a candy box showing our new design, the drawing being shaded to indicate color.

The applique for a candy box is of conventional thickness, two of which may be used to cover a six-sided candy box.

FIG. 1